H. H. STOUT.

FEEDING DEVICE FOR ROASTING FURNACES.
APPLICATION FILED FEB. 2, 1912.

Patented Aug. 12, 1913.

UNITED STATES PATENT OFFICE.

HARRY H. STOUT, OF BERKELEY, CALIFORNIA, ASSIGNOR TO GENERAL CHEMICAL COMPANY, OF NEW YORK, N. Y., A CORPORATION OF NEW YORK.

FEEDING DEVICE FOR ROASTING-FURNACES.

1,069,788.

Specification of Letters Patent. Patented Aug. 12, 1913.

Application filed February 2, 1912. Serial No. 675,004.

To all whom it may concern:

Be it known that I, HARRY H. STOUT, a citizen of the United States, and a resident of the city of Berkeley, county of Alameda, State of California, have invented a new, useful, and Improved Feeding Device for Roasting-Furnaces, of which the following, taken in connection with the accompanying drawings, is a specification.

- 10 My invention relates to roasting furnaces, especially such as are used for roasting pyrites or other ores, and such as are provided with stationary hearths upon which the ore is stirred and distributed by rakes 15 or plows affixed to a rotating arm, and has for its principal object the provision of means whereby the ore may be fed to the furnace automatically, periodically and in regulatable quantities.
- 20 An apparatus embodying my invention is illustrated in the accompanying drawings in which—

Figure 1 is a vertical section of a portion of a furnace equipped with my improved feeding mechanism; Fig. 2 is a plan view of a diametral portion thereof, showing particularly the primary feeding mechanism of my invention; Fig. 3 is an enlarged elevation of the secondary feeding mechanism, 30 the hopper thereof being in longitudinal vertical section; Fig. 4 is a longitudinal vertical section on the line 4—4 of Fig. 3. Fig. 5 is a cross section on the line 5—5 of Fig. 3 and Fig. 6 is a detailed view showing a 35 modified wiper.

The ore roasting furnace shown in the drawing belongs to the well-known type such as is shown and described, for instance, in the patent to John B. Francis Herreshoff, 40 No. 976,175, dated November 22, 1910.

The furnace comprises a cylindrical structure surrounded by a casing 1 and provided with a series superposed floors of which three only are shown and indicated in Fig. 45 1 by the reference characters 2, 3 and 4, the floors being alternately provided with peripheral apertures as 2' and 4' and central apertures, as 3'. The upper floor 2 constitutes a roof for the furnace and is utilized 50 as a hearth for supporting and drying the ore before it is fed to the burning hearths formed by the floors 3 and 4 and the other floors within the furnace. The gaseous products pass out through the port 1.

55 Extending vertically through the center

of the furnace is a rotatable shaft 5 to which is affixed a plurality of horizontally extending stirrer arms or rabble arms 6, 7 and 8. The arms 6 are preferably four in number and extend over the top or roof 2 and are provided preferably alternately with suitable plows 6' and suitable deflecting projections 6''. The ore fed to the roof of the furnace is stirred by the projections 6' and 6'' as the shaft 5 rotates. The projections 6'' are set at an angle so as to deflect the ore toward the peripheral aperture 2'. After being fed through the aperture 2' to the ore supporting hearth 3, the ore is stirred and deflected toward the opening 3' by the angularly arranged projections 7' on the rabble arms 7. After passing through the opening 3', the ore is stirred and deflected toward the opening 4' in the hearth floor 4 by the projections 8' of the rabble arms 8. There are 75 preferably two rabble arms 7 and two rabble arms 8. The deflecting projections on the rabble arms, obviously, are alternately oppositely arranged so as to properly deflect the ore toward the apertures in the hearths. 80

The shaft 5 is supported in a lower bearing (not shown) and an upper bearing 9 adjustably seated upon a plate 10 supported by channel irons 11, which latter extend across the top of the furnace and are suitably supported upon the casing 1. The shaft 5 is hollow and carries concentrically within it a tube 5' from which a cooling fluid, such as air, is adapted to pass into the spaces of the hollow rabble arms. After 90 traversing the arms the cooling fluid passes into the shaft 5 exteriorly of the tube 5' and escapes therefrom into the stack 12, provided with a suitable damper 12', by passing successively through apertures 13 in the shaft 5 and a space between the channels 11 formed by the partitions 11' and the closures 11'', the stack 12 being in communication with said space. 95

The plate 10 at one side of the shaft 5 is 100 formed with a vertical extension to which the primary feeding hopper 14 is suitably attached, the hopper being so positioned that ore fed into it is discharged upon the plate 10. The spout portion of the hopper 105 comprises a fixed portion 14' and a telescopic extension 14'' which is vertically slidable with reference to the fixed spout portion and which is adjustably held in position by means of bolt-and-nut devices 110

15. It is obvious that by manipulating these devices, the extension may be moved toward or away from the ore-supporting plate 10 and secured in any adjusted position.
- 5 Secured to the shaft 5 so as to rotate therewith is a radially extending arm 16 provided with an extension 16', the latter being arranged to pass in its rotation between the support 10 and the spout of the hopper 14.
- 10 The extension 16' is adjustably connected with the arm 16, by a suitable connection, as the pin and slot device 16''. By means of this adjusting connection, the relative distances between the extension and the plate 10 and 15 between the extension and the discharge orifice of the hopper may be varied as desired. The extension 16' projects angularly from the radial arm 16, as is clearly shown in Fig. 2 of the drawings.
- 20 Positioned in the opening 2' in the roof 2 is the hopper 17 of the secondary feeding device through which the dried ore is adapted to be fed upon the burning hearth 3. The spout portion of the hopper 17 comprises a fixed portion 17' and a telescopic tension 17'', the latter being vertically 25 slideable with respect to the former. In order to insure a ready and accessible adjustability of the extension 17'', I have provided a member 18 screw-threaded at its upper end and forked at its lower end, the forked portions being secured by suitable means, as, for instance, by the bolt and nut connections 18' to the extension 17'' and 30 the screw-threaded portion extending through a suitably supported bracket 19 and being engaged thereabove by a nut 20. It will be readily understood that manipulation of the nut 20 will result in a corresponding movement of the extension 17''.
- 35 Arranged on the extremity of one or more of the arms 7 is an extension 21, which, as the arm revolves, is adapted to sweep under the mouth of the hopper. The extension 21 is angularly disposed with respect to the radial arm 7 as shown particularly in Fig. 5 of the drawings. The mouth of the telescopic extension 17'' is cut at an angle as shown best in Fig. 4 of the drawings.
- 40 In Fig. 6 I have shown a slightly modified form of wiper which consists of a plate 22 suitably secured to and projecting from the end of the rabble arm.
- 45 In the operation of the furnace, ore is placed in the hopper 14 by which it is discharged upon the plate 10, until the discharged ore forms a pile, the top of which closes the mouth of the hopper. It is obvious 50 that the amount discharged will vary according to the position of the telescopic extension 17'' relatively to the plate 10, as well as according to the degree of fineness to which the ore has been reduced, the 55 amount of moisture in the ore and other

conditions. The automatic closing of the hopper orifice will take place also in a construction in which the orifice is at the side rather than at the bottom of the hopper spout. As the shaft 5 rotates, the wiper 16 passes between the plate 10 and the spout portion of the hopper and, obviously, moves a portion of the ore across the plate from the edge of which it drops upon the roof 2 therebelow. The portion 16' of the wiper being disposed at an acute angle to the direction of motion, the ore is pushed from beneath the spout in a direction which is at an acute angle to said direction of motion. The angle of the extension 16' is so arranged that the ore is caused to move in a general direction toward the opening 2' in the hearth below. This feature will be readily understood by referring to Fig. 2 of the drawings, the direction of rotation of the shaft being indicated therein by an arrow. If a proper amount of ore is not fed in this way for a particular adjustment of the telescopic extension 17'', the latter, obviously, may be adjusted to another position 90 in which a proper amount of ore will be fed, it being essential, however, that the spout extension be not lowered sufficiently in adjusting to come into contact with the wiper 16 in the rotation of the latter. As soon as 95 a portion of the pile of ore has been removed in this manner, a new pile is formed by ore discharging from the hopper. A portion of this pile is removed by the next passage of the wiper, immediately subsequent to which a new pile is formed. The repetition of this process, it will be seen, causes a periodic feeding of ore to the furnace, the feeding being both automatic and regulatable. After reaching the drying 100 hearth 2, the ore is stirred up and gradually moved toward the opening 2' by means of the arms 6. The secondary feeding means automatically feeds the ore from the hearth 2 to the hearth 3. The operation 105 of this feeding mechanism is similar to that of the primary feeding mechanism, as described above. The ore first passes through the hopper 17 and the telescopic extension thereof 17'' and forms a pile on the top 110 of the hearth 3 therebelow. When the pile thus formed reaches the mouth of the spout portion so as to close the same, the hopper begins to fill with ore. When the wiper 21 has passed beneath the hopper and moved 115 away a portion of the pile of ore therebelow, a new supply forms a new pile and more ore from the hearth 2 is moved into the hopper. The wiper 21 is angularly disposed with reference to the direction of motion thereof, similarly to the wiper 16, as 120 will be readily understood by an inspection of Fig. 5 of the drawings, in which the direction of rotation is indicated by the arrow therein. If the proper amount of ore is 125 130

not being fed by the secondary feeding device, the manipulation of the nut 20 will vary the position of the telescopic extension 17", as will readily be understood, so 5 as to insure a proper feeding of ore.

The wiper 22, shown in Fig. 6 of the drawings, may be substituted for either the wiper 16' or the wiper 21. In every case 10 the wiper moves in proximity to the discharge orifice of the hopper so as to remove a portion of the pile of ore. The wiper 22 obviously does not necessarily sweep directly between the ore support and the hopper spout but, may operate at one side of the 15 spout to remove a portion from the side of the pile of ore in which case the telescopic spout portion may be lowered without danger of its coming into contact with the wiper and the discharge may be thus wholly 20 shut off.

In practice the hopper 17 is at all times filled with ore. Gaseous products are thus prevented from escaping from the furnace through the feeding hopper. When adjusted 25 to proper position the telescopic extension does not require to be again moved during the operation of the furnace.

It will be seen that the two feeding devices are operatively related to each other. 30 If, for example, the primary device is adjusted to feed more ore than the secondary device is capable of feeding, either or both of said devices may be adjusted properly to regulate the feed. If, on the other hand, 35 the primary device furnishes an insufficient quantity of ore relatively to the secondary device, so that the secondary hopper is apt to become empty and permit gas to escape through it, either or both of the devices 40 may be adjusted in an obvious manner to insure the proper operation of the furnace.

It will of course be understood that various changes in the details of construction 45 may be made without departing from the spirit of my invention as defined by the appended claims.

I claim:

1. In an ore-roasting furnace, the combination of a support for the ore, a hopper positioned above said support and provided 50 with a telescopic extension, and a wiper movable in proximity to the discharge orifice of said extension, substantially as and for the purpose described.

2. In an ore-roasting furnace, the combination of a support for the ore, a hopper positioned above said support, the depending spout portion thereof comprising a telescopic extension, means for adjustably positioning said extension and a wiper movable 60 in proximity to the discharge orifice of said extension, substantially as and for the purpose described.

3. In a roasting furnace having a stationary top and a stationary hearth therebelow, 65 the combination of a hopper affixed to said top and having a telescopic spout portion extending toward said hearth, a stirrer arm adapted to rotate above said hearth and a wiper extending from said arm and adapted to move in proximity to the mouth of said extension, substantially as and for the purpose described.

4. In a roasting furnace having a stationary top and a stationary hearth therebelow, 75 the combination of an adjustable primary feed hopper, an adjustable secondary feed hopper, means for automatically feeding ore from the primary hopper to the top and for automatically feeding ore from the secondary hopper to the hearth, and means for feeding to the secondary hopper the ore discharged from the primary hopper, substantially as and for the purpose described.

In testimony whereof, I have hereunto 85 set my hand in the presence of two subscribing witnesses.

HARRY H. STOUT.
